UNITED STATES PATENT OFFICE

MICHAEL J. KOHLER, OF OAKLAND, CALIFORNIA, ASSIGNOR TO THE NATIONAL NUT COMPANY, OF OAKLAND, CALIFORNIA, A CORPORATION OF CALIFORNIA

DESIGN FOR A NUT BUTTERING MACHINE

Application filed December 2, 1932. Serial No. 46,284. Term of patent 14 years.

To all whom it may concern:

Be it known that I, MICHAEL J. KOHLER, a citizen of the United States, residing at Oakland, in the county of Alameda and State of California, have invented a new, original, and ornamental Design for Nut Buttering Machines, of which the following is a specification, reference being had to the accompanying drawing, forming part thereof.

Fig. 1 is a front elevation of the article, showing my new design.

Fig. 2 is a plan view.

Fig. 3 is an end elevation.

I claim:

The ornamental design for a nut buttering machine as shown.

MICHAEL J. KOHLER.
